UNITED STATES PATENT OFFICE.

JAMES S. FRASER, OF BOSTON, MASSACHUSETTS, ASSIGNOR OF ONE-HALF TO IRA C. MOULTON, OF BOSTON, MASSACHUSETTS.

SAFETY APPLIANCE FOR SUBMARINE VESSELS.

1,139,409.

Specification of Letters Patent. Patented May 11, 1915.

Application filed June 17, 1914. Serial No. 845,598.

To all whom it may concern:

Be it known that I, JAMES S. FRASER, a citizen of the United States, and resident of Boston, in the county of Suffolk and State 5 of Massachusetts, have invented certain new and useful Improvements in Safety Appliances for Submarine Vessels, of which the following is a specification.

This invention has for its object to enable 10 the occupants of a submarine vessel to send a ventilating tube or air conduit to the surface of a body of water in which the vessel may be submerged, so that in case the vessel is unable to rise, the occupants may obtain 15 air from above and may also indicate to rescuers the location of the vessel.

The invention consists in the improvements which I will now proceed to describe and claim.

20 Of the accompanying drawings forming a part of this specification: Figure 1 represents a side elevation of a portion of a submerged submarine vessel, equipped with a safety appliance embodying my invention; Fig. 2 represents a section on line 2—2 of Fig. 1; Fig. 3 represents an enlargement of a portion of Fig. 2; Fig. 4 represents a top plan view of the portion shown by Fig. 3; Fig. 5 represents a fragmentary sectional 25 view showing the inflatable bag and its socket member, hereinafter referred to, in a fully expanded condition; Fig. 6 represents a top plan view of the part termed the stopper; Fig. 7 represents a sectional view of a part of the deck of the vessel and the safety attachment stored in compact form therein, and not in use; Fig. 7^a represents a section on line 7^a—7^a of Fig. 7; Fig. 8 represents a side view of portions of the receptacle and its cover shown by Fig. 7; Fig. 9 represents a section on line 9—9 of Figs. 7 and 8; Fig. 10 represents a view similar to Fig. 9, showing a releasing position; Fig. 11 represents a section on line 11—11 of Fig. 1.

The same reference characters indicate the same or similar parts in all the views.

In the drawings: 12 represents the deck of a submarine vessel, said deck having an 50 opening through which passes an elongated flexible non-collapsible ventilating tube 13. Said tube is attached at its inner end portion to the vessel and is of suitable length to enable its outer end to be projected above 55 the surface of a body of water on the bottom

of which the vessel may rest. I have provided means controlled from within the vessel for projecting the tube upwardly from the coiled and stored position shown by Fig. 7 to the position shown by Fig. 1, 60 in which *a* represents the surface and *b* the bottom of a body of water in which the vessel is submerged.

As the said projecting means 1 employ an inflatable bag 15 of collapsible and watertight construction, said bag being connected with the outer end of the tube 13, and an elongated collapsible inflating tube 16 connected at one end with the bag 15 and at its other end with the vessel, the inflating tube inclosing the ventilating tube and being enough larger than the latter to form an air space between the two tubes when the inflating tube is distended or internally supported by air.

75 The inner end of the inflating tube is connected with means within the vessel for supplying air under pressure, such as a tank 18 containing compressed air. As here shown the inner end of the inflating tube is attached to a rigid collar 20 having an internally threaded flange 21 which is screwed upon a threaded nipple 22 extending through the deck 12 and having a screw-thread engagement therewith. 23 is a nut screwed upon the nipple 22 and bearing on the upper surface of the deck. Said nut supports the flange 21, which acts as a lock nut. 24 is a nut screwed upon the nipple 22 and bearing on the under-side of the deck. 25 is a screw-threaded cap or flange corresponding in form to the flange 21 and screwed on the inner end of the nipple 22 and against the nut 24, the flange 25 also constituting a lock-nut. The cap 25 is connected by one or more tubes 26 with the air tank 18. The tubes 26 may be provided with valves 27, and when these valves are opened there is a direct communication between the tank 18 and the inflating tube 16 through the nipple 22. The inner end portion of the ventilating tube extends through the nipple 22 and is held in a central position therein by ears 28 (Fig. 7^a) on the collar 20, said ears being separated by air spaces 29, which permit air to pass from the nipple 22 into the inflating tube.

100 The ventilating tube 13 is constructed to resist external pressure so that it will not be collapsed by pressure of water against it, said tube being preferably composed 105

either wholly or in part of a helically wound metal strip or strips forming a flexible non-collapsible metal tube of well known construction. The outer end of the tube 13 has an enlargement 13^a forming a chamber into which a stopper 30 is adapted to swing inwardly by gravity from the position shown by Figs. 2 and 3 to that shown by Fig. 5, the stopper being connected by a hinge 31 with the enlargement 13^a. The stopper and the enlargement 13^a are preferably of rectangular form, the stopper being provided with a beveled margin adapted to close against a beveled seat 32 formed on the interior of the enlargement 13^a.

The object of the stopper is to prevent entrance of water into the ventilating tube when the latter is submerged and while it is rising to the surface. The stopper is held or confined in its closed position by a circular stud member 33 formed on the outer side of the stopper and having a grooved periphery and an expandible socket member composed of a lip 34 forming a part of the bag 15 and a circular helical spring 35 inclosed in said lip and adapted to contract the lip and cause it to engage the grooved periphery of the stud member 33 as indicated by Figs. 3 and 4. It will be seen therefore that while the lip 34 is in its normal contracted position it forms a socket or coupling member which engages the stud member 33 and prevents the latter and the stopper 30 from swinging inwardly, and that when said socket is expanded it releases the stopper, which thereupon opens by gravity.

36 represents a flexible diaphragm attached at one edge to the outer end of the tube 13 and to a tubular shank 13^b formed on the enlargement 13^a, and at its opposite end to the bag 15 near the lip 34. Said diaphragm is of annular form and is adapted to prevent water from entering the main portion of the bag 15 when the stopper 30 is opened as shown by Fig. 5.

The bag 15 may be composed of inner and outer layers of flexible waterproof textile fabric, said layers being separated from each other, and an intermediate filling 15^a of buoyant material such as ground cork. The bag is therefore inherently buoyant and is adapted to rise to the surface when liberated whether inflated or not.

When the device is not in use the bag and the tubes 13 and 16 are stored in compact form on the deck in a receptacle 37 attached to the deck, said receptacle having a buoyant cover 38 adapted to be released to liberate the bag and tubes as hereinafter described. When the bag and tubes are thus stored, the tubes are disposed in coils, as indicated by Fig. 7, the bag being collapsed and stored within the coils. The tubes 16 are partially flattened or collapsed when thus stored, so that the tubes 13 and 16

may be stored in a receptacle of minimum height.

The cover 38, which may be composed of spaced-apart layers of fabric and an intermediate filling 38^a of ground cork, is provided with a flexible flange 40, which is preferably an extension of one of the fabric layers and is adapted to be pressed closely against the exterior of the receptacle 37.

41 represents a metal band having overlapping ends, as indicated by Figs. 9 and 10. To one of said ends is pivoted at 42 a lever 43 having an ear 44 adapted to engage the opposite end of the band. 45 represents a bolt passing loosely through one arm of the lever 43 and through orifices formed in the band through the flange 40 and through the wall of the receptacle 37. Said bolt has an orifice at its inner end adapted to receive a locking pin 46, which is movable in guides 47 within the receptacle 37. Said pin passes through an orifice in the deck and is connected at its lower end with a lever 48 pivoted at 49 within the vessel. When the lever 48 is depressed from the position shown by Fig. 7 it withdraws the pin 46 from the bolt 45. The band 41 is sufficiently resilient to normally spring open or expand, as indicated by Fig. 10, and does so expand when the bolt 45 is released. The expansion of the band causes the ends of the band and lever 43 and the bolt 45 to assume the positions shown by Fig. 10, the cover flange 40 being thus released and caused by its own buoyancy to rise in the water and liberate the bag and tubes. The lever 43, when moved from the position shown by Fig. 10 to that shown by Fig. 9, acts to close the band and cause it to clamp the flange 40 against the receptacle.

The operation of the appliance is as follows:— Assuming that the vessel is submerged and resting on the bottom *b* and is unable to rise an operator within the vessel connects the air tank 18 with the inflating tube 15 and moves the lever 48 to release the cover 38 of the receptacle 37. The inflation of the bag 15 and its inherent buoyancy causes it to rise quickly from the receptacle and uncoil the tubes until the bag reaches the surface and projects above the same, as indicated by Figs. 1 and 2, the stopper 30 remaining closed and preventing water from entering. The air pressure that accumulates in the bag up to the time that it reaches the surface of the water is not sufficient to expand the lip or socket 34. An increase of the air pressure after the bag reaches the surface causes a further expansion of the bag and an enlargement of the socket 34, as indicated by Fig. 5, the stopper 33 being thus released and permitted to swing by gravity into the enlargement 13^a. Free communication is thus established between the interior of the vessel and the atmosphere.

through the ventilating tube 13, sufficient air being admitted to the vessel through said tube to sustain the lives of the people in the vessel. At the same time the bag 15 constitutes an indicator enabling rescuers to locate the submerged vessel. The bag may be provided with one or more electric lamps 50 suitably connected through the tubes with a source of electrical energy within the vessel. Wires 51 may be conducted through the tubes and bag to the interior of the bag to be connected by a rescuing party with a telephonic apparatus whereby conversation may be carried on between the rescuing

party and the occupants of the vessel.

The deck 12 may be provided with a nipple 52 (Fig. 11) closed at its outer end by an externally removable outer cap 53 and at its inner end by an internally removable inner cap 54, nuts 55 and 56 being interposed between said caps and the deck. The cap 54 may be provided with a hollow extension 57 which practically fills the interior of the nipple 52. The object of the construction last described is to enable communication to be established between the exterior and interior of the vessel through the nipple 52 by a diver who may descend to the vessel with a tube, or with a ventilating tube and an inflating tube, connected as shown with an internally threaded collar 21 adapted to be screwed onto the upper end of the nipple 52. The diver removes the cap 53 and substitutes the collar 21 therefor. After this, the cap 54 may be removed by the occupants of the vessel and replaced by a collar 25 to establish communication between the interior of the vessel and the ventilating and inflating tubes. The object of the extension 57 which is removed with the cap 54 is to reduce to the minimum the quantity of water admitted to the nipple 52 when the outer cap is removed, and consequently the quantity of water entering the vessel when the inner cap is removed.

The inner cap 54 may be a closed cap, as indicated by full lines (Fig. 11), or it may be constructed like the cap 25 (Fig. 7), and provided with nipples 58 as shown by dotted lines, for connection with suitable air pipes, so that air may be forced outwardly into the inflating tube, or drawn inwardly through the ventilating tube.

The inner end of the ventilating tube 13 may be coupled to a pipe 60 within the vessel, said pipe being connected with the intake of a suction fan 61 adapted to draw air through the ventilating tube into the vessel. The inwardly opening stopper opened as described by gravity cannot be closed by air rushing downwardly into the ventilating tube, such air having a tendency to hold the cover from swinging toward its closed position.

Having described my invention, I claim:

1. The combination with a submarine ves-

sel, of an elongated flexible ventilating tube secured to the hull of the vessel and communicating with the interior thereof, means controlled from within the vessel for raising the outer end of said tube to the surface of a body of water in which the vessel may be submerged, an inwardly opening, water-excluding stopper at the outer end of the ventilating tube adapted to be opened by gravity, means for confining the stopper in its closed position, and means controlled from within the vessel for releasing the stopper and permitting it to open by gravity and admit air to the tube.

2. The combination with a submarine vessel, of an elongated flexible non-collapsible ventilating tube secured to the hull of the vessel and communicating with the interior thereof, an inherently buoyant, collapsible inflatable bag secured to the outer end portion of the ventilating tube, a collapsible bag-inflating tube inclosing the ventilating tube and extending from the bag to the vessel, means within the vessel for inflating the bag through the inflating tube, a stopper adapted to exclude water from the ventilating tube, and means controlled from within the vessel for opening said stopper to permit air to pass through the ventilating tube.

3. The combination with a submarine vessel, of an elongated flexible non-collapsible ventilating tube secured to the hull of the vessel and communicating with the interior thereof, an inherently buoyant, collapsible inflatable bag secured to the outer end portion of the ventilating tube, a collapsible bag-inflating tube inclosing the ventilating tube and extending from the bag to the vessel, means within the vessel for inflating the bag through the inflating tube, a stopper adapted to exclude water from the ventilating tube, means controlled from within the vessel for opening said stopper to permit air to pass through the ventilating tube, confining means for holding the said bag and tubes stored compactly on the deck of the vessel when the bag and inflating tube are collapsed, and means controlled from within the vessel for rendering said confining means inoperative, and liberating the bag and tubes.

4. The combination with a submarine vessel, of an elongated flexible non-collapsible ventilating tube secured to the hull of the vessel and communicating with the interior thereof, an inflatable bag secured to the outer end portion of the ventilating tube, a collapsible bag-inflating tube inclosing the ventilating tube and extending from the bag to the vessel, means within the vessel for inflating the bag through the inflating tube, a stopper adapted to exclude water from the ventilating tube, means controlled from within the vessel for opening said stopper to permit air to pass through the ventilating tube.

ventilating tube, a holder on the deck of the vessel for compactly storing said bag and tubes when the bag and inflating tube are collapsed, said holder having a buoyant 5 cover and cover-securing means, and means controlled from within the vessel for rendering the cover-securing means inoperative and thus releasing and permitting the flotation of said cover and liberating the bag 10 and tubes.

5. The combination with a submarine vessel, of an elongated flexible ventilating tube secured to the hull of the vessel and communicating with the interior thereof, an inflatable 15 bag secured to the outer end portion of the ventilating tube, a bag-inflating tube extending from the bag to the vessel, means within the vessel for inflating the bag through the inflating tube, a stopper hinged 20 in the outer end of the ventilating tube and adapted to swing inwardly, said stopper having a circular outwardly projecting stud member, an expandible socket member on the bag having a spring whereby it is normally 25 closed on the stud member to hold the stopper closed, said socket member being expandible to release the stopper by a predetermined expansion of the bag, and a flexible water excluding diaphragm arranged 30 to prevent the entrance of water into the bag through the opening surrounded by said socket member.

6. The combination with a submarine vessel, of an elongated flexible ventilating tube secured to the hull of the vessel and communicating with the interior thereof, an inflatable bag secured to the outer end portion of the ventilating tube, a bag-inflating tube extending from the bag to the vessel, means 35 within the vessel for inflating the bag through the inflating tube, a stopper adapted to exclude water from the ventilating tube, means controlled from within the vessel for opening said stopper to permit air to 40 pass through the ventilating tube, a holder on the deck of the vessel for compactly storing said bag and tubes, said holder having a buoyant cover provided with a flexible flange embracing the mouth of the receptacle, a clamping band embracing said flange and adapted to normally expand and release the flange, a lever pivoted to one end 45 of the band and having an ear adapted to engage the opposite end of the band, a sliding bolt carried by said lever and extending 50 through the band, the flange, and the wall

of the receptacle, a locking pin movable in guides within the receptacle and detachably engaging said bolt, the band being held in clamping engagement with the flange by 55 said pin, bolt and lever, and released by the withdrawal of the pin from the bolt, and means within the vessel for withdrawing the pin from the bolt.

7. The combination with a submarine vessel, of an elongated flexible ventilating tube secured to the hull of the vessel and communicating with the interior thereof, means controlled from within the vessel for raising the outer end of said tube to the surface of a 65 body of water in which the vessel may be submerged, an inwardly opening, water-excluding stopper at the outer end of the ventilating tube adapted to be opened by gravity, and means for drawing air into the vessel 70 through said tube, the entering air having a tendency to hold the stopper in its open position.

8. The combination with a submarine vessel, of an elongated flexible ventilating tube 80 secured to the hull of the vessel and communicating with the interior thereof, means controlled from within the vessel for raising the outer end of said tube to the surface of a body of water in which the vessel may be 85 submerged, an inwardly opening, water-excluding stopper at the outer end of the ventilating tube adapted to be opened by gravity, means for confining the stopper in its closed position, and pneumatically operated 90 means controlled from within the vessel for releasing the stopper and permitting it to open and admit air to the tube.

9. The combination with a submarine vessel having an opening in its deck, of an externally threaded nipple extending through said opening and projecting above and below the deck, outer and inner nuts engaged with said nipple and bearing respectively on the upper and lower surfaces of the deck, 95 an internally threaded outer cap detachably coupled to the outer end of the nipple and bearing on the outer nut, and an internally threaded inner cap detachably coupled to the inner end of the nipple and bearing on 100 the inner nut.

In testimony whereof I have affixed my signature, in presence of two witnesses.

JAMES S. FRASER.
